US00D606416S

(12) United States Design Patent
Walker

(10) Patent No.: US D606,416 S
(45) Date of Patent: * Dec. 22, 2009

(54) COLLAPSIBLE CONTAINER

(75) Inventor: Allison Janet Walker, 2109 Azalea Cir., Decatur, GA (US) 30033

(73) Assignee: Allison Janet Walker, Atlanta, GA (US)

() Term: 14 Years

(21) Appl. No.: 29/317,063

(22) Filed: Apr. 22, 2008

(51) LOC (9) Cl. 09-01

(52) U.S. Cl. D9/552; D9/558; D9/571

(58) Field of Classification Search D9/516, D9/529, 537, 548, 539-540, 549, 550, 551, D9/552, 558, 563, 564, 571, 574, 683; 215/381-385

(57) CLAIM

The ornamental design for a collapsible container, as shown and described.

DESCRIPTION

FIG. 1 is a perspective view of a collapsible container showing my new design;

FIG. 2 is a left side view thereof;

FIG. 3 is a front view thereof;

FIG. 4 is a right side view thereof;

FIG. 5 is a back view thereof;

FIG. 6 is a bottom view thereof; and,

FIG. 7 is a top view thereof.

The top portion and bottom portion of the collapsible container is shown in broken lines for illustrative purposes only and forms no part of the claimed design.

1 Claim, 6 Drawing Sheets
